UNITED STATES PATENT OFFICE.

JOZSEF LOSONCY, OF READING, PENNSYLVANIA, ASSIGNOR OF ONE-HALF TO LOUIS BEDECS, OF READING, PENNSYLVANIA.

GARBAGE-CAN.

1,251,984.

Specification of Letters Patent.

Patented Jan. 1, 1918.

Application filed March 22, 1917. Serial No. 156,600.

To all whom it may concern:

Be it known that I, JOZSEF LOSONCY, a subject of the King of Hungary, residing at Reading, in the county of Berks and State 5 of Pennsylvania have invented certain new and useful Improvements in Garbage-Cans, of which the following is a specification.

This invention relates to certain new and useful improvements in garbage cans.

10 The primary object of the invention is the provision of a receptacle for garbage being automatically closable and normally maintained in that position although the same is readily opened by the foot of the operator 15 whenever desired for use and maintained open until released.

A further object of the device is to provide a receptacle for garbage that is easy to manufacture and possesses great strength, 20 the same being sanitary in its arrangement and readily operable without employing the hands for opening and closing the device.

In the drawing forming a part of this application and in which like designating 25 characters refer to corresponding parts throughout the several views:—

Figure 1 is a side elevation of the device closed, the same being illustrated by dotted lines in its open position.

30 Fig. 2 is a rear elevational view thereof.

Fig. 3 is a horizontal transverse sectional view of the same taken upon line III—III of Fig. 1, and,

35 Fig. 4 is an enlarged detail sectional view of the spring hinge portion of the device.

The present arrangement may provide a receptacle of any desired dimensions and cross-sectional formation, the same being herein illustrated as a can 10 mounted upon 40 a plurality of supporting legs 11, a circular disk or cover 12 being hinged thereon.

A bracket 13 projects upwardly from the can 10 and is arranged with a vertical slot 14 longitudinally therein through which a 45 rear extension 15 of a cleat 16 secured diametrically upon the top of the lid 12 is pivoted by means of a pintle 17.

A forwardly projecting flange 18 at the top of the bracket 13 has a depending lug 50 19 upon its forward oblique side 20 for mounting the upper end of a helical spring 21, the lower end of which is seated over a similar lug 22 upon the aforementioned cleat 16. It will be understood that the spring

21 normally maintains the lid 12 in its closed 55 position upon the can 10.

A foot lever 23 is pivoted as at 24 to a post 25 swivelly arranged within a central post 26 while the lever 23 extends outwardly between two oppositely projecting angular 60 racks 27. A rod or link 28 connects the lever 23 as at 29 with the loop 30 at the outer free end of the cleat extension 15 while an enlarged foot engaging tread plate 31 is provided at the outer free end of the lever 65 23, the upper face of the said plate being preferably roughened.

It will be understood that by placing the foot upon the plate 31 and depressing the lever 23, that the rod 12 will be elevated 70 upon its pintle 17 against the action of the spring 21 while a slightly lateral movement imparted to the said lever will position the same beneath the horizontal portion 32 of one of the racks 27, thereby maintaining the 75 lid open. When desired to have the lid 12 assume its closed position, the plate 31 is given a lateral impulse releasing the same from the retaining rack 27 and permitting the spring 21 to close the lid 12, which action is assisted by the weight of the said lid. The entire device is preferably formed 80 of metal, preventing the same from burning while the lid 12 may be maintained substantially air-tight by the spring 21, rendering 85 the device sanitary, it being noted that the lid may be opened by the foot of the operator and automatically closed when released.

What I claim as new is:—

1. A garbage device comprising a can, a 90 closure hinged thereto, a post swiveled to the bottom of the can, and an operating foot lever for the lid pivoted to the said post.

2. A garbage receptacle comprising a can, a hinged closure for the said can, an operating lever for the lid centrally swiveled beneath the said can, and angular retaining brackets oppositely arranged with respect to the lever having horizontal portions positioned adjacent thereto. 95

3. A garbage device comprising a can, a closure hinged thereto, a post swiveled to the bottom of the can, an operating foot lever for the lid pivoted to the said post, and angular retaining brackets oppositely arranged with respect to the lever having horizontal portions adjacent thereto. 105

4. A device of the class described compris-

ing a can, elevating legs for the can, a bracket carried by the can having an overlying top flange, a closure lid for the said can, a cleat secured to the said lid having an extension pivoted to the said bracket, and a closure spring tensioned between the said cleat and flange.

5. A device of the class described comprising a can, elevating legs for the can, a bracket carried by the can having an overlying top flange, a closure lid for the said can, a cleat secured to the said lid having an extension pivoted to the said bracket, a closure spring tensioned between the said 10 cleat and flange, a centrally depending boss carried by the can, a post swivelly mounted in the said boss, a lever pivoted to the said boss radially extending outwardly of the can having a tread plate at its free end, and a pivoting link between the said lever and extension.

6. A device of the class described comprising a can, elevating legs for the can, a

bracket carried by the can having an overlying top flange, a closure lid for the said can, a cleat secured to the said lid having an extension pivoted to the said bracket, a closure spring tensioned between the said cleat and flange, a centrally depending boss carried by the can, a post swivelly mounted in the said boss, a lever pivoted to the said boss radially extending outwardly of the can having a tread plate at its free end, a pivoting link between the said lever and extension, angular retaining racks arranged in spaced relations at the opposite sides of the lever having horizontal receiving portions adapted for detachably receiving said lever therebeneath when in its depressed laterally displaced position with the lid in its open 35 arrangement.

In testimony whereof I affix my signature.
JOZSEF LOSONCY.
